PROCESS AND APPARATUS FOR
DISPENSING PASTES

Riewen Riegler, Buffalo, N. Y., assignor to National Aniline and Chemical Company, New York, N. Y., a corporation of New York

Application April 29, 1933, Serial No. 668,480

2 Claims. (Cl. 221—120)

This application relates to dispensing dye pastes and other similar slow-flowing, dough-like, highly viscous pastes. It is directed specifically to a method and apparatus for rendering such pastes, more particularly quick indigo pastes, sufficiently fluid so that they can be extruded into containers in which they are to be packed.

Certain pastes, such as quick indigo paste, which is indigo white in admixture with various substances such as one or more of the following: molasses, dextrin, Binderin (residue from the sulfite digestion of cellulose), corn syrup, etc., and glue, gluten, gelatin, casein, albumin, etc., have high cohesive properties and are viscous, non-elastic, and stiff and tend to more or less set, upon standing, so that they hardly will flow at all. These pastes at ordinary temperatures are generally too stiff to stir and if stirring is attempted, tend to move or rotate as a mass so that by ordinary methods they can be packed out through discharge orifices into containers only with great difficulty if at all.

Prior to the present invention such dye pastes have been packed into containers for shipping, sale, etc. by manual labor. The process is a tedious one and it is difficult not only to fill a container to capacity but to get uniform quantities of materials into containers of the same size. The dough-like consistency of these products seems to cause the formation of voids or air spaces within the containers and to prevent the occupancy of such spaces by the paste. Manual packaging of said dye pastes, in addition to other objections, usually results in an excessive exposure of the dye pastes to the oxidizing action of the air and causes a reduction in the quality of the packed product.

In accordance with the method of the present application, the dye paste is subjected to a to and fro or reciprocal agitation during the dispensing process. This agitation causes the paste to become relatively fluid so that it will readily be discharged, upon the application of a plunger action, into the container or other vessel to which it is to be supplied.

The apparatus of the invention preferably comprises a vertically disposed cylindrical vessel having an outlet at the lower end and being provided with a reciprocating agitator operated by a suitable motor during the dispensing process so as to render the paste fluid.

In order that the method and apparatus of my invention may be better understood, there follows a description of a preferred embodiment

thereof. The description should be considered in connection with the accompanying drawing in which,

Fig. 1 discloses an elevation, partly in section, of the preferred apparatus;

Fig. 2 is a detail view showing the arrangement of the outlet of the dispensing device;

Fig. 3 is a detail plan view of the outlet of Fig. 2;

Fig. 4 is a section on line 4—4 of Fig. 1 showing the hopper shaped upper end of the dispensing device.

With particular reference to Fig. 1, the numeral 1 designates the body or chamber of a dispensing apparatus. The body 1 may be suitably supported on the structural member 2 so that the upper end thereof extends through the floor above the main portion of the container. The upper end of container 1 may be provided with a suitable closure cap 3 that may be suitably arranged so as to be removable during the filing of the dispenser 1. It is preferably constructed in two pieces as shown for ready removal without interference with the agitator shaft to be hereinafter more particularly described. Numeral 4 represents a tiltable vessel from which the paste may be introduced into the dispensing apparatus. At its lowermost end the dispenser 1 is provided with a frusto-conical portion 5 having thereon a hinged member 6 forming an outlet aperture and, in the position shown in solid lines, constituting a continuation of the frusto-conical portion 5. The outlet side of member 6 is closed by a gate 7.

Extending vertically within the chamber 1 is provided a shaft 8 mounted on bearings 9, 10, and 11 so that it may be oscillated or vibrated vertically. This shaft 8 is provided with a plurality of blades 12 on that portion of the shaft located within the chamber 1. These blades are suitably arranged so that by vertical oscillation of the shaft 8 the blades produce an agitation of the contents of the chamber 1. The vertical oscillation of shaft 8 may be effected by a suitable motor 13 operating, through a suitable gear train, and adjustable eccentric 14 connected with a toggle member 15 that oscillates about a fixed pivot 16 and actuates the collar 17 fixed to shaft 8.

In Fig. 2, showing in detail the outlet portion 5 of the chamber 1, the hinged piece 6 is adapted to swing between a position flush with outlet 22, and a position indicated in dotted lines 6'. The outlet opening of the end member 5 is somewhat larger than the small end of the tapered piece 6,

while the larger end of this piece corresponds substantially with the size of the opening of the member 5, so that when the member 6 is in the position shown in solid lines in Fig. 2 a continuous 5 tapered outlet is provided in the casing 1 to the outlet opening 18. When a larger opening is desired the cap 6 may be swung to the position indicated in dotted lines and thus the opening 22 will constitute the outlet.

10 Suitable means (not shown) may be provided to maintain the hinged piece 6 in the two extreme positions. A hand hole 19 also is provided for gaining access to the interior of the dispensing device.

15 Mounted on the hinged member 6 and arranged to pivot thereon at 20 is the gate or cutting member 7. This gate is adapted to be opened to permit the flow of the paste from the container and to be closed to stop the flow therefrom. It 20 may be provided with a knife edge so that on closing the outlet of the dispenser the gate serves to cut off the putty-like or dough-like shaft of paste extending from the dispenser. An additional gate 21 may be provided operating in a 25 similar or different manner with respect to the open end of member 5 so that when the larger opening is in use and hinged member 6 is swung to the side the gate 21 will serve to check the flow of paste from the dispenser. This gate 21 30 is shown in the drawing as a sliding gate adapted to slide laterally across the opening 22.

Fig. 4 shows the flared upper end portion 23 of container 1 designed so that the material may be readily introduced into the dispensing device. The flared portion is designed to correspond in size with the vessel 4 which is positioned so that when tilted as indicated in dotted lines 35 the lip of vessel 4 will approximately coincide with the flared portion 23.

40 In the operation of the apparatus above described the indigo paste prepared in vessel 4 is introduced into the casing 1 of the dispenser by tipping the vessel 4 to the position indicated at 4'. The dispenser having been filled with paste, 45 the cap 3 is placed thereon.

When it is desired to remove the paste from the container, the shaft 8 is vertically oscillated as by starting the motor 13. The motor oscillates the shaft 8 with an up and down motion so that 50 the blades 12 as well as the shaft itself agitate the paste contained in the casing 1. A rate of oscillation of 100 strokes per minute with an agitator having a two inch stroke has been found very satisfactory but this may be varied between 55 wide limits as the rate of oscillation does not proportionally vary the fluidity. This agitation renders the paste sufficiently fluid so that upon opening the gate 7 the paste, due to plunger action of the shaft and to gravity, will flow from the 60 container. The end 24 of shaft 8 is located directly above the outlet orifice 18 and in proxim-

ity thereto, so that the vertical oscillation of the shaft assists in forcing the paste through the orifice as a plunger would do. The container into which material is to be supplied is located below the outlet opening and when it has been filled or when it is desired to place another container below the opening the gate is closed, thus cutting off the extruded shaft of paste and permitting it to fall into the container. Another container then may be placed under the opening 10 and the gate 7 again opened.

In the filling of small containers, especially those having relatively small mouths, the piece 6 is retained in a closed position so as to properly regulate the discharge of paste. However, 15 in filling larger containers, such as drums, etc., the piece 6 is swung aside to permit exposure of the larger opening 22, thus gaining a more rapid rate of discharge from the dispenser.

The fluidity of pastes such as quick indigo depends to some but small extent upon the rate at which they are agitated. In order to obtain the maximum degree of fluidity it is only necessary that the vertical oscillation of the shaft 8 and blades 12 be fairly rapid. The length of 25 the stroke in the vertical oscillation of the shaft 8 and blades 12 will affect the rate of discharge of the material from the dispenser. The rate of oscillation may be suitably controlled by a resistance on the motor where a motor is employed, 30 or suitable gear trains, belts, etc., or other power transmission means adapted for this purpose. The length of the stroke may be regulated by means of the adjustable eccentric 14.

I claim:

1. A dispenser for pastes comprising a vertically disposed cylindrical vessel having a tapered upper end to constitute a charging hopper therefor and a frusto-conical lower end of diminishing diameter having a discharge opening at the apex thereof, a vertically disposed shaft within said container having agitator blades affixed thereto, said shaft being adapted for vertical oscillation, one end of said shaft being disposed in proximity to said discharge opening whereby said shaft is adapted to act as a discharge plunger for material in said container, and a motor arranged for oscillating said shaft.

2. A dispenser for pastes comprising a vertically disposed cylindrical vessel having a frusto-conical end of diminishing diameter having a discharge opening at the apex thereof, a vertically disposed shaft within said container having agitator blades affixed thereto, said shaft being adapted for vertical oscillation, one end of said shaft being disposed in proximity to said discharge opening whereby said shaft is adapted to act as a discharge plunger for material in said container, and a motor arranged for oscillating said shaft.
